UNITED STATES PATENT OFFICE.

BERNIS M. SHIPLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed June 30, 1924. Serial No. 723,190.

This invention relates to cash registers, and more particularly to the mechanism for controlling the opening of the cash drawers.

The principal object of the invention is the provision of mechanism for controlling the release of cash drawers from a plurality of banks of keys.

A specific object is the provision of mechanism for releasing the same drawers from a plurality of banks of keys.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said figures:

Fig. 1 is a section through a machine, in which the present invention is embodied, taken just to the right of the third control bank.

Fig. 2 is a detail side elevation of the racks for positioning the drawer releasing mechanism under control of the first and second control banks.

Fig. 3 is a fragmentary rear elevation of the mechanism for positioning the release mechanism for the cash drawers.

Fig. 4 is a detail perspective view of the mechanism for releasing the selected cash drawer.

Fig. 5 is a detail top plan view of the racks operated by the first and second banks of control keys.

General description.

This invention is shown embodied in a cash register of the type shown and described in the patent to Frederick L. Fuller No. 1,394,256. In machines of this type it is usually customary to provide three banks of control keys. Such machines can also be equipped with any number of cash drawers from one to nine, one drawer being provided for every three clerks using the machine. In previous machines of this type the release of the cash drawer was controlled by a single bank of keys, but this machine has been designed so that each cash drawer may be released by a key in each of the three control banks. It will be evident from the following description of the inven-

tion that the construction shown herein is of a flexible nature, and it is not intended to confine the invention to the particular form shown herein, nor its use to the particular type of cash register disclosed. 60

Keyboard and differential mechanism.

The three banks of control keys, which are all of the keyboard with which the present invention is concerned are identically the same, and may represent twenty seven clerks having access to nine cash drawers, with the corresponding key in each of the three banks controlling the opening of one cash drawer. The mechanism in general for these three control banks of keys is similar to that shown in detail and described in the above mentioned Fuller patent, with this exception, that the interlocking mechanism necessary in the Fuller patent which compels the depressing of one key in each of the three control banks before the machine can be operated, is omitted in this invention. The description, thereof, in this application will therefore be as much simplified as possible. 80 For the sake of convenience, the control banks will be referred to by number herein, for example, as banks 1, 2 and 3, from right to left. Each bank contains nine keys 30 (Fig. 1), which are slidably mounted in a key frame 31 supported at its upper and lower ends by rods 32 and 33. These keys are adapted to be held in their depressed position during the operation of the machine, and restored to their undepressed position at the end of such operation in a manner which is very well known and the description of which is accordingly omitted here. 90

The differential mechanism for the release banks is also old and well known and only a brief description thereof will be included in this application. A latch member 34 is pivotally supported by an arm 35 and a bell crank 36, which are in turn carried by a differentially movable member 37. This member is pivoted on a stud 38 and is driven by an invariably moved segment 39, also pivoted on the stud. The segment 39, as is well known, is given its invariable movement by means of a link 40, a Y-shaped member 41 and a pair of cams 42 and 43 which are fast on a shaft 44. This shaft is the main drive shaft of the machine and receives one complete rotation on every item 110

entering operation thereof, thereby causing the Y-shaped member 41 to rock first clockwise and then counter-clockwise about its pivot. On the clockwise movement of the 5 Y-shaped member the segment 39 and the differentially movable member 37 will be rocked clockwise until the forward end of the bell crank lever 36 comes into contact with the inner end of whichever one of the 10 keys 30 has been depressed. When this occurs, the latch member 34 will be disconnected from a shoulder on the invariably moved segment 39, and the differentially movable member 37 will be stopped in a 15 position corresponding to the key depressed.

If no key in a bank has been depressed the latch will be broken by means of a zero stop pawl 45 which lies in the path of a member 46 shown broken away, pivoted on the stud 48 and connected to the bell crank lever 36 by a slot and pin connection. The operation of this mechanism is old and very well-known, and if any further description thereof is desired it may be found in the application for Letters Patent of the United States No. 576,924, filed July 20, 1922, by B. M. Shipley.

When the invariably moved segment 39 is rocked counter-clockwise to its normal position a surface 47 thereof will strike a pin 48, on the differentially movable member 37, and return this member to its normal position. Pivoted to the member 37 is a beam 49, which at its opposite end is bifurcated and cooperates with a pin 50 carried by a link 51. The link 51 is pivoted at its upper end to a segment 52, which is adapted to position both the corresponding indicators and the desired totalizer in a manner which is described in the above referred to patent. At its lower end, the link is pivoted to an arm 53 loose on a rod 54, supported by the machine side frames. The arm 53 appropriate to the third control bank has secured thereto a segment gear 55, the teeth of which mesh with teeth 56 formed on the forward end of a rack 57, the forward end of which is slidably mounted on a cross member 58, the rear end being supported by the machine frame. The rear end of the rack 57 carries teeth 59, which mesh with a gear 60 loosely mounted on a shaft 61 supported by two brackets 62 and 63 (Fig. 3) supported on the base of the machine.

The links 51, which correspond to the first and second banks of control keys, are pivotally connected to arms 64 and 65, respectively, (Fig. 2) to which are secured segment gears 66 and 67. The segment gear 66, appropriate to the first control bank, meshes with teeth 68 formed on the forward end of a rack 69. The segment gear 67, appropriate to the second control bank, meshes with teeth formed on a rack 70. Both of the racks 69 and 70 are slidably

mounted at their forward ends on the cross member 58 and at their rear ends slide on the base of the machine (Figs. 2 and 3). The rack 69 has a plate 71 secured thereto, which carries teeth meshing with a 70 pinion 72 fast on a short shaft 73, the ends of which extend through slots 74 formed in the racks 69 and 70. The rack 70 carries a plate 75, which has teeth meshing with a pinion 76, also fast on the shaft 73. Loosely mounted on the shaft 73, equi-distant between the racks 69 and 70, is an arm 77, the rear end of which slides on the base of the machine. The arm 77 carries teeth 78 on its upper edge meshing with a pinion 79 secured to the shaft 61.

Only one key in all three of the control banks can be depressed on a single operation. If the key depressed is in the third control bank, it can be seen from Fig. 1 85 that the differential movement of the member 37 will be imparted through the beam 49 and link 51 to the arm 53 and segment gear 55, which will in turn, through the rack 57, rotate the gear 60 to an extent 90 corresponding to the key depressed. As this gear 60 is loose on the shaft 61, however, it is evident that differential movement imparted to this gear will have no effect on the shaft 61.

If, however, the key depressed is in either the first or second control banks, then the differential movement will, through the parts above mentioned, be given to either the rack 69, or the rack 70. As shown in Fig. 2, the rack 69 is in its "9" position, and the rack 70 is in its "0" position. If, on the next operation of the machine, the "9" key in the second control bank is depressed, the rack 69 will be returned to its "0" position, and the rack 70 will be moved to its "9" position. It can be seen that as the movement of these two racks, in this particular instance, is the same, only in opposite directions, and the plates 71 and 75 cooperate with opposite sides of the 100 pinions 72 and 76, there will be no relative movement of the arm 77 on this operation, and therefore the shaft 61 will not be rotated. When a key in the third transaction bank is depressed, then the rack 69 will 105 simply return to its "0" position, in which position the plates 71 and 75 are directly opposite, with the pinions 72 and 76 in approximately the center of said racks. It can be seen that as the rack 69 returns to "0", the 110 rack 70, being held motionless, the pinions 76 will simply roll over the teeth on the plate 75 and the arm 77 will be carried rearwardly. The teeth on the arm 77 will thereupon 115 rotate the pinion 79 fast on shaft 61 and rotate this shaft to its "0" position. It can be seen that, due to the above construction, the pinions 72 and 76 are rotated the difference 120 between the movement of the racks 69 and 70, and this movement will therefore, 125 130

through the arm 77 and pinion 79, rotate the shaft 61 differentially, in accordance with the key depressed in either of the first or second control banks.

5

Drawer mechanism.

The drawer mechanism of the present machine is of conventional design in most respects, and it is not believed that a specific 10 description of the mechanism is essential to an understanding of the invention. The machine contemplated by the present invention is provided with nine cash drawers, only the upper two of which are shown in Fig. 3. 15 Each of the cash drawers 90 is slidably mounted in an opening in the base of the machine. On the back of each of the cash drawers a bracket 91 is bolted, to which is pivoted a drawer latch 92 (Fig. 1), having a 20 shoulder 93 engaging a hardened plate laid in a bar 94 extending laterally across the rear of the machine and supported by vertically extending members 95. There is one of these bars 94 for each drawer. The latch 25 92 is held in its latching position by a spring 96 stretched between a projection on the latch 92 and a pin on the bracket 91. When the drawer is unlatched, in a manner which will presently be described, it is moved forwardly out of the drawer cabinet under the 30 influence of two springs 97, the construction and function of which are old and well known.

The cash drawer to be released is selected 35 by the key depressed in any of the three control banks. If the key depressed is in the third control bank the gear 60 will be rotated differentially in accordance therewith. This gear is connected by means of clutch 40 member 98 (Fig. 3) with a spiral gear 99 loose on the shaft 61. This spiral gear meshes with a spiral pinion 100 (Figs. 1 and 4) fast on a short vertical shaft 101. At its lower end, the shaft 101 carries a member 45 102, the front and back of which are flattened, and which is adapted to be inserted into a corresponding opening in a cylindrical member 103 carried on the upper end of a shaft 104. It can be seen from Fig. 4 50 that due to the construction of these parts a rotary movement of the spiral pinion 100 will be transferred to the shaft 104, and also a vertical movement of the shaft 104 and the member 103 can be effected without raising 55 the spiral pinion 100.

Fast on the shaft 104 are a plurality of lugs, or fingers, 105 which are differentially and spirally disposed about the periphery of the shaft, one opposite each of the cash 60 drawers. Thus, if the "9" key, in the third control bank, is depressed and through the differential mechanism the shaft 104 is rotated to its "9" position, the lug 105, appropriate to the lowermost, or ninth, cash 65 drawer will be moved into position to coop-

erate with this drawer. Pivots mounted on the frame 94, for each drawer, is a lever 106, the movement of which is limited by a pin 107 which projects through an opening in said lever. This lever extends laterally 70 of the machine and normally lies just above the latching arm 92 for its appropriate cash drawer. It is evident that when the right hand end of the lever 106 is raised, the left hand end will be lowered, and therefore the 75 latch arm 92 will be pushed downwardly far enough to disengage its shoulder 93 from the plate in bar 94, and thereby permit the springs 97 to force the drawer forwardly to its open position.

Parallel to the shaft 104 is a shaft 108, which carries fingers 109 in exactly the same relation as the fingers 105 previously described. At its upper end, the shaft 108 carries identically the same mechanism as 80 that previously described in connection with the shaft 104, and it is therefore thought to be unnecessary to describe this mechanism again at this point. It is thought to be sufficient to say that the shaft 108 receives its movement through a spiral pinion 110 (Figs. 3 and 4) which cooperates with a spiral gear 111 fast on the right hand end of the shaft 61. It will be remembered that the shaft 61 is rotated differentially through 85 the pinion 79 and arm 77, driven by either the rack 69 or the rack 70, depending upon whether the control key was depressed in the first, or second, banks. In other words, when a key is depressed in the first, or 90 second, banks, the shaft 108 will be differentially rotated in order to bring the appropriate finger 109 into position to release the cash drawer appropriate to the key depressed, while if a key in the third control 95 bank is depressed, the shaft 104 will be rotated to accomplish the same function.

Means for tripping the drawer latch.

No matter which of the shafts 104 or 108 is selected to release the cash drawer they will both be operated in order to release the desired drawer. It can be seen from Fig. 4 that the member 103 and its corresponding member on the shaft 108 both have a horizontally extending channel 112 cut therein. Fast on a shaft 113, adjacent each of the shafts 108 and 104, is a U-shaped member 114 which carries two pins 115 projecting into the channel 112. Fast 110 on the shaft 113 is an arm 116, the free end of which rests on the left hand end of a lever 117 pivoted on a stud 118 of the frame. The opposite end of the lever 117 carries a roller 119 which cooperates with the periphery of a cam 120 fast on a shaft 121. This 115 shaft is the main printer drive shaft shown in the above mentioned patent and receives a complete clockwise rotation (Fig. 4) upon every operation of the machine. When this 120 125 130

rotation takes place the cam 120 will rock the lever 117 clockwise, which will in turn rock the arm 116, shaft 113 and U-shaped members 114 also clockwise, thereby raising the member 103 and its counterpart on shaft 108 together with shafts 104 and 108 upwardly. The cam 120 will then permit the parts to return to their normal position, as shown in Fig. 4. Upon the upward movement of the shafts 104 and 108 the lug 105, or the lug 109, depending upon in which bank of control keys a key was depressed, will cooperate with a downwardly extending projection 122, or 123, carried by an arm 124, and will rock this arm clockwise. The arm 124, at its left hand end, has a bent portion lying just beneath the right hand end of the lever 106 appropriate to each drawer, and therefore, if this arm 124 is rocked by the lug on either of the shafts 104 or 108, it is evident that the lever 106 will be rocked counterclockwise, thereby disengaging the latch 92 and releasing the particular cash drawer selected.

25 While the form of mechanism herein shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow.

What is claimed is:

35 1. In a cash register having a plurality of cash drawers, two banks of control keys, a differential mechanism actuated under control of each of said banks of keys, a horizontal rack operated by each of said differential mechanisms, a shaft extending through 40 slots in both of the racks and carrying two pinions each meshing with the teeth of one of said racks, a member pivoted on said shaft and having teeth formed thereon, a gear meshing with said member, a shaft carrying 45 said gear, and means actuated by the movement of said last mentioned shaft for selecting the drawer corresponding to whichever key in either of said banks has been depressed.

55 2. In a cash register having a plurality of cash drawers, two banks of control keys, a differential mechanism actuated under control of each of said banks of keys, a horizontal rack operated by each of said differential mechanisms, a shaft extending through slots in both of the racks and carrying two pinions each meshing with the teeth of one of said racks, a member pivoted on 60 said shaft and having teeth formed thereon, a gear meshing with said member, a shaft carrying said gear, and means for giving said last mentioned shaft an invariable movement on every operation to release the selected cash drawer.

65 3. In a machine of the class described, the combination of a drawer, a plurality of banks of keys, a differential for each bank of keys, and a single means separately operable by each of said differentials for causing 70 said drawer to be opened.

75 4. In a machine of the class described, the combination of a plurality of drawers, a plurality of banks of keys, a differential for each bank, and a drawer selecting means 80 separately operable by each of said differentials under control of said keys.

85 5. In a cash register, the combination of a plurality of banks of keys, a plurality of cash drawers normally retained in inaccessible position, means for causing said cash drawers to be moved into accessible position, and means for controlling said first mentioned means separately from each of said banks of keys.

90 6. In a cash register, the combination of a plurality of banks of keys, a plurality of drawers, a rotatable drawer selecting shaft, and means for rotating said shaft, separately operable under control of any key in any one of said banks.

95 7. In a cash register, the combination of a plurality of banks of keys, a plurality of drawers, a rotatable drawer selecting shaft, and means for rotating said shaft the same extent under individual control of keys in different banks.

In testimony whereof I affix my signature.

BERNIS M. SHIPLEY.
